S. MARCUS.

ARTIFICIAL EYES FOR DOLLS, DISPLAY FIGURES, AND THE LIKE.

APPLICATION FILED AUG. 16, 1917.

1,252,469.

Patented Jan. 8, 1918.

UNITED STATES PATENT OFFICE

SAMUEL MARCUS, OF NEW YORK, N. Y.

ARTIFICIAL EYES FOR DOLLS, DISPLAY FIGURES, AND THE LIKE.

1,252,469.

Specification of Letters Patent.

Patented Jan. 8, 1918.

Application filed August 16, 1917. Serial No. 186,491.

To all whom it may concern:

Be it known that I, SAMUEL MARCUS, a citizen of the United States, and a resident of New York city, in the county of New York and State of New York, have invented certain new and useful Improvements in Artificial Eyes for Dolls, Display-Figures, and the like, of which the following is a specification.

10 The invention relates to improvements in the manufacture of eyes for dolls and other purposes, such as display figures, and the purpose of the invention is to provide an eye of novel structure and also novel means 15 for securing a pair of eyes within the head of a doll or other figure in such manner that the eyes may roll to closed position when the doll is turned from a vertical to a horizontal position and also to roll to open position when the doll is turned from a horizontal to a vertical position.

The eyes are formed of hollow shells of celluloid or equivalent material and mounted on plates connected to a bridge-piece 25 which connects the eyes in a pair and to which the customary weight for effecting the rolling of the eyes is secured. The bridge-piece connecting the eyes has pivotally secured to its central portion an upwardly extending plate adapted to be secured to the inner surface of the forehead of a doll by means of shellac or other adhesive applied to said surface over said plate. My purpose is to sell the eyes in pairs 30 to manufacturers of dolls. The eyes being of celluloid or like material on their exterior are substantially unbreakable and afford a desirable finish.

The more important features of the invention reside in the means provided by me 40 for mounting the eye-shells upon the ends of the bridge-piece, and in respect to these features of the invention I mount the celluloid shells upon substantially hemi-spherical metal shells and provide in the rear open 45 sides of the celluloid shells metal plates which may be secured upon the ends of the bridge-piece for connecting the pair of eyes thereto.

50 In accordance with my invention either eye may be adjusted lengthwise of the bridge-piece or laterally of the face of the doll so that the eyes may be adapted to the openings in the face of a doll regardless of 55 the irregularities which are to be found in

dolls' heads. In accordance with my invention also the eyes may be given an angular motion on the bridge-piece so as to further adapt them to the openings provided for the eyes in dolls' heads.

60 The invention will be fully understood from the detailed description hereinafter presented, reference being had to the accompanying drawings, in which:

Figure 1 is a substantially central vertical 65 section through the head of a doll, the same being partly broken away, equipped with the features of my invention;

Fig. 2 is an enlarged rear elevation of a pair of eyes and co-operating parts shown 70 independently of the head of the doll;

Fig. 3 is a horizontal section through the same, taken on the dotted line 3—3 of Fig. 2;

Fig. 4 is a central vertical section, taken 75 through one of the eyes, on the dotted line 4—4 of Fig. 2;

Fig. 5 is a rear elevation, with the connecting parts broken away, of a pair of eyes showing a modified means for securing the eyes to the bridge-piece;

80 Fig. 6 is a horizontal section, through one of the eyes of the same, taken on the dotted line 6—6 of Fig. 5;

Fig. 7 is a central vertical section through the same eye taken on the dotted line 7—7 85 of Fig. 5;

Fig. 8 is a central vertical section through a further modified eye-construction taken on the dotted line 8—8 of Fig. 9;

Fig. 9 is a horizontal section through the same taken on the dotted line 9—9 of Fig. 8;

Fig. 10 is a rear elevation with the connecting parts broken away of a further modified construction of eye embodying my invention, and

95 Fig. 11 is a horizontal section through the same taken on the dotted line 11—11 of Fig. 10.

In the drawings, 10 designates a portion of the head of a doll, 11 the bridge-piece, 100 12 the eyes for the doll, 13 a weight suspended by a rod 14 rigidly connected with said bridge-piece, and 15 a plate having eyes 16 at its lower bifurcated end in which the bridge-piece 11 is loosely mounted. The 105 bridge-piece 11, eyes 12, weight 13 and rod 14, are pivotally suspended from the plate 15, which extends upwardly from between the eyes 12 and may be readily conformed and secured to the inner surface of the fore- 110

head of the doll by means of shellac or the like, as denoted at 17. I regard the securing of the eyes and coöperating parts by means of the vertically and centrally disposed plate 15 as of considerable advantage. I have found that cheek-pieces applied at the outer edges of the eyes to be secured within the side portions of a doll's head, as disclosed in my application 151,938, filed 5 March 2, 1917, while of great advantage when the dolls' heads are uniformly constructed, lack the advantage of the centrally disposed plate 15 for suspending the eyes and their parts, since said plate 15 is bendable and may be conformed to the inner surface of the forehead of a doll without difficulty.

The bridge-piece 11 may be a simple straight rod of wire against which the suspending rod 14 may be rigidly secured by solder, as at 18.

The eyes 12 are composed of exterior celluloid substantially hemi-spherical shells 19 disclosing the pupil and iris, as usual, inner 10 hemi-spherical metal shells or bearings 20 upon which the shells 19 are closely but freely mounted, and plates 21 to which the ends of the bridge-piece 11 may be secured by screws 22 so as to position the eyes on 15 said bridge-piece in an adjustable manner to the end that the eyes may be arranged to suit the openings in the face of the doll to receive them. The plates 21 may be of varied construction, but in Figs. 2 and 3 I illustrate said plates as being formed from sheet 20 metal and as having loops 23 pressed forwardly therefrom to receive as seats the ends of the bridge-piece 11, an integral bar being formed intermediate the planes of the 25 loops 23 and receiving the securing and adjusting screws 22, as will be readily understood on reference to Figs. 2, 3 and 4. The plates 21 are of cup-shape and afford curved 30 edge flanges 25 fitting the inner portions of the shells 19 and constituting curved extensions of the inner edges of the bearing shells 20, against which edges the inner 35 annular edges of the plates 21 abut. The metal shells 20 are recessed at opposite edges 40 to receive the end portions of the bridge-piece 11, and at their facing or inner sides the celluloid shells 19 are recessed, as at 26, so as to permit the adjustment of said shells 19 on the ball-like metal shells 20 for the 45 purpose of properly locating the iris of each eye within the opening therefor in the face of the doll. The recesses 26 in the shells 19 freely receive or straddle end portions of the bridge-piece 11, and either shell 50 19 may be turned toward the right or left or up or down on its shell 20 so as to secure the proper adjustment of the eye. Each eye 55 12 therefore comprises an outer celluloid shell 19, an inner shell 20 conforming thereto and upon which the shell 19 is mounted,

and a metal plate 21 fitting within the inner portions of the shell 19 and abutting against the rear edges of the shell 20, and the plate 21 is of a construction adapting it to be adjustably secured upon an end portion of 70 the bridge-piece 11, which may, in this construction, be simply a straight rod of wire.

Fig. 5 represents a modification as to the method by which the eyes 12 may be secured to the bridge-piece 11. In the construction 75 shown in Figs. 5, 6 and 7 I make use of the same suspending rod 14, celluloid shells 19 and metal shells 20 that I have described hereinbefore in connection with the illustration presented in Figs. 1 to 4 inclusive, but 80 in lieu of the plates 21 shown in Figs. 1 to 4 inclusive I make use of, in the construction shown in Figs. 5, 6 and 7, substantially corresponding metal plates 27 fitting within the rear portions of the shells 19 and abutting against the rear edges of the metal shells 20 and having flanges 28 corresponding with the flanges 25 of the construction shown in Figs. 2, 3 and 4, but as a modification said plates 27 are formed with horizontal outwardly bent groove-portions 29 and vertical slots 30 crossing the same at their central portions. The groove-portions 29 of the plates 27 fit against the rear side of the bridge-piece 11, and as means for securing the end portions of the bridge-piece to the eyes, I provide in the construction shown in Figs. 5, 6 and 7 small plates 31 of wedge-shape which are passed through 90 the slots 30 from the front side of the plates 100 27 and have openings 32, 33, the opening 32 being to receive the end portion of the bridge-piece 11 and the opening 33 to receive a wedge 34 which I drive through the opening 33 of each plate 31 for the purpose 105 of binding the plate 31, plate 27 and bridge-piece 11 firmly together. The wedge 34 for each eye not only passes through the slot 33 of the plate 31, but engages the rear horizontal surface of the groove-portion 29 of 110 the plate 27. When the wedge 34 is loosened by being driven laterally, in the present instance outwardly toward the outer edge of the eye (Fig. 6), the plate 31 becomes 115 loosened from the bridge-piece 11 and the eye may be adjusted on said bridge-piece and then re-tightened by driving the wedge 34 toward the inner edge of the eye. Figs. 5, 6 and 7 differ from the construction shown in Figs. 1 to 4 inclusive merely in the detail 120 of securing the eyes upon the bridge-piece 11, one construction employing the screws 22 and the other the wedges 34.

In Figs. 8 and 9 I illustrate a further modification so far as the means for securing the eyes upon the bridge-piece is concerned, but not otherwise. In the construction shown in Figs. 8 and 9 the celluloid shells 19 and metal shells 20 remain the same as in the construction shown in Figs. 3 and 130

4, but in the modification illustrated in Figs. 8 and 9, in lieu of the plates 21, 27 hereinbefore referred to, I make use of thicker plates (numbered 35) which are bored 5 through to receive the ends of the bridge-piece 11, as will be readily understood on reference to Figs. 8 and 9. The plates 35 fit within the rear portions of the shells and perform the duties of the flanges 25, 28 hereinbefore referred to, the edges of the plates 10 35 being curved to constitute continuations of the curved outlines of the metal shells 20 and to receive in a suitable manner the rear curved portions of the celluloid shells 19, the 15 shells 20 and the edges of the plates 35 forming a sectional ball upon which the shells 19 may be given a sliding or rocking motion for their adjustment to the openings in the face of the doll. The plates 35 are 20 equipped on their rear sides with suitable openings for the screws 36 by which the eyes may be fastened to the bridge-piece 11, the screws 36 serving the same purposes as the screws 22 hereinbefore mentioned.

25 In Figs. 10 and 11 I illustrate a further modification of my invention in respect to the means for securing the eyes upon the bridge-piece and locking the shells 19 in adjusted position upon the inner hemispherical metal shells or bearings 20, and in 30 Figs. 10 and 11 the numeral 19 denotes the celluloid shell disclosing the pupil and iris, and 20 the hemi-spherical bearing hereinbefore described. Within the shell 19 and engaging the circumferential edges of the bearing 20 is a metal plate 37, which plate has a circumferential flange 38 fitting within and conforming to the curvature of the shell 19; the plate 37 also has a central boss portion 39 to receive a screw 40 which engages the bridge-piece 11 and serves to secure the eye on said bridge-piece. The boss 39 may be pressed up from the metal of the plate 37. Upon the screw 40 is a supplemental plate 41 45 which extends transversely of the rear portion of the eye and has a threaded aperture through which the screw 40 passes. The plate 41 preferably has at one end a finger 42 and at the other end two fingers 43 which straddle the recess in the shell 19 through 50 which the bridge-piece 11 extends. The fingers 42, 43 are, when the shell 19 has been adjusted on the bearing 20, bent against said shell 19 so as to bind the same in its adjusted 55 position, all this being for the purpose of preventing the shell 19, during the use of the doll, from shifting from its original adjusted position. The plate 37 is only another mechanical form for the plates 21 60 shown in Figs. 2 and 3, but in addition to what is shown in Figs. 2 and 3, Figs. 10 and 11 illustrate additional means, as the plate 41, for locking the shell 19 after it has been adjusted to its required position. The boss 65 39 is apertured transversely to receive the

end of the bridge-piece 11, and hence said bridge-piece is held between said boss and the adjacent surfaces of the plate 37.

In all of the constructions shown I provide eyes which may be adjusted along the 70 bridge-piece and in which the eyes are formed of shells 19 of substantially hemispherical or partly globular outline and are adjustable in all directions upon interior metal shells 20 which support the shells 19 75 and prevent said shells 19 from being indented or disfigured from blows which, in the absence of the metal shells 20, might pierce the shells 19 or drive them inwardly. In all of the constructions shown the eyes 80 contain within their rear portions metal plates adapted to be adjustably secured upon the ends of the bridge-piece 11 and which plates are held within the rear curved portions of the shells 19, said plates affording 85 bearing surfaces for said shells and said shells by their curvature binding the said plates in position against the rear edges of the metal shells 20.

What I claim as my invention and desire 90 to secure by Letters Patent, is:

1. An eye for dolls and the like, comprising a substantially hemi-spherical shell constituting the exterior of the eye, an inner bearing member of corresponding outline 95 upon which said outer shell is mounted, a plate within the rear portion of the outer shell and in close relation to the inner edges of said inner member, and means for fastening the eye to a bridge-piece of a pair of 100 eyes, said shell being slidably adjustable on said bearing member.

2. An eye for dolls and the like, comprising a substantially hemi-spherical shell constituting the exterior of the eye, and an inner bearing member of corresponding outline 105 upon which said outer shell is closely but slidably mounted for adjusting the same.

3. An eye for dolls and the like comprising a substantially hemi-spherical shell constituting the exterior of the eye, an inner bearing member of corresponding outline 110 upon which said outer shell is closely but slidably mounted for adjusting the same, and a plate at and connected with the rear 115 portion of the outer shell to which a bridge-piece for a pair of eyes may be secured.

4. An eye for dolls and the like comprising a substantially hemi-spherical shell constituting the exterior of the eye, an inner 120 bearing member of corresponding outline upon which said outer shell is closely but slidably mounted for adjusting the same, and a plate within the rear portion of the outer shell and having a curved edge portion 125 constituting a continuation of said inner bearing member, and which plate serves as a means for connecting the eye to a bridge-piece for a pair of eyes.

5. An eye for dolls and the like compris- 130

- 4
- ing a substantially hemi-spherical shell constituting the exterior of the eye, an inner bearing member of corresponding outline upon which said outer shell is closely but 5 slidably mounted for adjusting the same, and a plate within the rear portion of the outer shell and having a curved edge flange constituting a continuation of said inner bearing member and also a seat for a 10 bridge-piece for a pair of eyes and means for securing the bridge-piece on said seat.
6. An eye for dolls and the like comprising a substantially hemi-spherical shell constituting the exterior of the eye, an inner 15 bearing member of corresponding outline upon which said outer shell is closely but slidably mounted, and a plate at and connected with the rear portion of the eye having curved seats bent therefrom and a bar 20 between said seats adapted to receive a screw, said seats being adapted to receive the end portion of a bridge-piece for a pair of eyes.
7. In combination, a pair of eyes for a 25 doll and the like, a bridge-piece connecting said eyes, a weight suspended from the middle of said bridge-piece, and an upwardly extending plate in which said bridge-piece is freely mounted and which is adapted to 30 be secured to the inner surface of the forehead of a doll, for suspending said eyes, bridge-piece and weight.
8. In combination, a pair of eyes for a 35 doll and the like, a bridge-piece connecting said eyes and having rounded end portions, and plates at and connected with the rear portion of the eyes and having bearings to be slid upon said end portions of the bridge-piece and conforming thereto, and whereby 40 said eyes are permitted to have independent angular adjustment on said end portions of the bridge-piece.
9. In combination, a pair of eyes for a
- doll and the like, said eyes having outer shells, a bridge-piece connecting said eyes, 45 and means suspending said bridge-piece, and plates at and connected with the rear portion of the eyes and having curved edge flanges adapted to permit angular adjustment of the outer shell of the eyes and also 50 means for connecting the eyes with the end portions of said bridge-piece.
10. In combination, a pair of eyes for a doll and the like, and a bridge-piece connecting said eyes, said eyes each comprising a substantially hemi-spherical celluloid shell constituting the exterior of the eye, an inner substantially hemi-spherical metal plate closely fitting within said shell, and a plate within the rear portion of said shell 60 and engaging the edges of said hemi-spherical plate and providing means for connecting the eye with the end portion of the bridge-piece.
11. In combination, a pair of eyes for a 65 doll and the like, and a bridge-piece connecting said eyes, said eyes each comprising a substantially hemi-spherical celluloid shell constituting the exterior of the eye, an inner substantially hemi-spherical metal 70 plate closely fitting within said shell, and a plate within the rear portion of said shell and engaging the edges of said hemi-spherical plate and providing means for connecting the eye with the end portion of the 75 bridge piece, said plate at the rear portion of the eye having curved edges engaged by the rear portion of said shells.

Signed at New York city, in the county of New York and State of New York, this 80 10th day of August, A. D. 1917.
